(57) **CLAIM**

The ornamental design for an access tag holder, as shown and described.

DESCRIPTION

The article of this design patent application is an access tag holder for use in mobile vehicles for the purpose of containing and displaying an access tag in situations such as when traveling on toll roads or when attempting to access restricted areas. The access tag holder of the present design has open front and back sides to allow for the display of the access tag to a tag reader.

FIG. 1 is a perspective view of the front side of the design.

FIG. 2 is a perspective view of the back side of the design.

FIG. 3 is a perspective view of the top of the design.

FIG. 4 is a perspective view of the bottom of the design.

FIG. 5 is a perspective view of the left side of the design. FIG. 6 is a perspective view of the right side of the design; and,

FIG. 7 is a front and bottom view of the design.
